(57) **CLAIM**

The ornamental design of a gusset, as shown and described.

DESCRIPTION

FIG. 1 is a front view of a gusset showing our new design; FIG. 2 is a left side view of the embodiment of FIG. 1; FIG. 3 is a right side view of the embodiment of FIG. 1; FIG. 4 is a top view of the embodiment of FIG. 1; and, FIG. 5 is a bottom view of the embodiment of FIG. 1.

The broken lines are provided for illustrative purposes only and form no part of the claimed design. In addition, the portions of the gusset that are not shown in the drawings, if any, do not form any part of the claimed design.

1 Claim, 1 Drawing Sheet
